CORE BAG MACHINE

Bertie C. Golden, Richmond, Va., assignor, by mesne assignments, to Millhiser Bag Company, Incorporated, a corporation of Virginia

Filed June 6, 1958, Ser. No. 740,469

36 Claims. (Cl. 112—104)

This invention relates to new and useful improvements in the art of bag making, and in particular concerns itself with the making of bags having a tag or label stitched at one edge thereto. Bags of this general type are widely used for retaining cores or samples taken in the well drilling industry and for this reason are frequently referred to in the art as "core bags."

One type of a machine for making bags of this general nature is disclosed in my Patent No. 2,313,433, issued March 9, 1943, wherein a continuously moving web of material is doubled longitudinally upon itself to form the side walls and bottom of bags with an open mouth and wherein tags are inserted at predetermined intervals between the folds of the continuously moving web, whereupon the web is cut into individual bags each having a tag therein disposed so that when the cut edges are subsequently stitched, the tag is secured by one edge to the bag. As already noted, in the machine according to my prior patent the tags are inserted into the folded or doubled web, while the same is continuously moving, and the arrangement is such that the tag is affixed to the bottom edge of the finished bag.

The principal object of the present invention is to provide an improved and modified arrangement whereby the tag may be affixed to one side edge rather than to the bottom edge of successive bag members and whereby the tag inserting operation is performed after the moving web is cut into individual bag members which are held relatively stationary at the cutting position while the tag is being inserted. As a result, the arrangement of the machine is not only simplified, but much greater accuracy is attained in proper positioning and securing of the tag in relation to the finished bag.

An important feature of the present invention involves the provision of improved means for separating the cut side edges of the bag to facilitate the insertion of the tag therebetween, such means utilizing a pair of coacting suction units one of which holds one side edge of the bag relatively stationary while the other moves the superposed side edge away from the relatively stationary edge during insertion of the tag.

Another important feature of the present invention involves the provision of means for feeding tags in a continuous strip form to the bags, the strip of tags being easier to handle, feed and otherwise manipulate than individual tags which often adhere together or miss being picked up by the feeding means.

In conjunction with the last mentioned feature, another important feature of the present invention resides in the provision of means including a photo-electric cell which scans the strip of tags and is adapted to detect markings located at spaced points thereon, for controlling the feeding of the tag strip in an intermittent manner, coordinated with the production of individual bags from the web.

As in the machine according to my prior Patent No. 2,313,433, the bags completed by the present invention have the tag at the inside thereof but are inside out. As such, they are subsequently delivered to a stringing machine of a conventional type which not only inserts a string into a hem at the mouth of the bags, but also reverses the bags from the inside out so that the tag is ultimately at the outside of the finished bag.

With the above more important objects and features

2

in view and such other objects and features as may become apparent as this specification proceeds, the invention will be understood from the following description taken in conjunction with the accompanying drawings, 5 wherein like characters of reference are used to designate like parts and wherein for illustrative purposes:

FIGURE 1 is a plan view of a finished bag with its tag, the bag having been processed by a conventional stringing machine after its fabrication by a machine in 10 accordance with the present invention, so that it has been reversed from inside out and the tag is at the outside of the bag;

FIGURE 2 is a diagrammatic illustration showing the flow of both web material and the tag strip in the machine according to the invention, as well as bags complete 15 with tags made by such machine;

FIGURE 3 is a fragmentary top plan view of the bag making and tagging machine in accordance with the invention;

FIGURE 4 is a fragmentary side elevational view thereof;

FIGURE 5 is a fragmentary sectional view showing the web cutting means, taken substantially in the plane of the line 5—5 in FIGURE 3;

FIGURE 6 is a sectional detail, taken substantially in the plane of the line 6—6 in FIGURE 5;

FIGURE 7 is a fragmentary sectional view, taken substantially in the plane of the line 7—7 in FIGURE 3;

FIGURE 8 is a fragmentary sectional view of the bag 30 opening and feeding means, taken substantially in the plane of the line 8—8 in FIGURE 3 and shown on an enlarged scale;

FIGURE 9 is a fragmentary top plan view of the subject shown in FIGURE 8;

FIGURE 10 is a fragmentary sectional view similar to that shown in FIGURE 8 but showing the guide of the carrier raised;

FIGURE 11 is a fragmentary sectional view similar to those shown in FIGURES 8 and 10 but showing the carrier at its primary station;

FIGURE 12 is a fragmentary sectional view similar to that shown in FIGURE 11 but showing the upper suction unit in its raised position;

FIGURE 13 is a fragmentary sectional view similar to that shown in FIGURE 12 but showing the clamp of the suction unit in its clamping position;

FIGURE 14 is a fragmentary sectional view of the suction units, taken substantially in the plane of the line 14—14 in FIGURE 9;

FIGURE 15 is a sectional detail, taken substantially in the plane of the line 15—15 in FIGURE 14;

FIGURE 16 is a horizontal sectional view in fragmentary form showing the operating cams, cam levers and associated parts, taken substantially in the plane of the line 16—16 in FIGURE 4;

FIGURE 17 is a fragmentary vertical sectional view, taken substantially in the plane of the line 17—17 in FIGURE 16;

FIGURE 18 is a fragmentary vertical sectional view 60 showing the means for reciprocating the carrier of the web cutter;

FIGURE 19 is a sectional detail, taken substantially in the plane of the line 19—19 in FIGURE 3;

FIGURE 20 is a fragmentary sectional view, taken substantially in the plane of the line 20—20 in FIGURE 3;

FIGURE 21 is a sectional detail, taken substantially in the plane of the line 21—21 in FIGURE 20;

FIGURE 22 is a sectional detail, taken substantially in the plane of the line 22—22 in FIGURE 3;

FIGURE 23 is a longitudinal sectional detail of the valve means for the suction units; and

FIGURE 24 is a fragmentary elevational view, taken

substantially in the plane of the line 24—24 in FIGURE 3.

The accompanying FIGURE 1 illustrates a finished bag 10 after the same has been processed by a conventional stringing machine, such as that shown in my Reissue Patent No. 23,196, which inserts a string 11 into hems 12 at the mouth of the bag and reverses the bag inside out so that the tag or label 13 is at the outside of the bag. The closed bottom of the bag is indicated at 14 and the opposite side edges 15 of the bag have been secured together by lines of stitching 16. The tag 13 is secured by one of its edges between the side edges 15 at one side of the bag, through the medium of the line of stitching 16 passing through the side edges of the bag between which the tag is inserted.

The machine in accordance with this invention completes the bag to the point where it is inside out and the tag 13 is at the inside thereof, so that it is ready for delivery to the stringing machine above mentioned. The bag making material in the machine according to the invention is in the form of a continuous web 10a, unwound from a suitable roll 10b and doubled longitudinally upon itself as indicated at 10c in FIGURE 2, whereupon it is intermittently fed between a pair of rollers 17 to what may be called a primary work station 18. At this station successive portions of the doubled web of a size sufficient to form a bag are successively clamped against the table top 23 and individual bag members cut from the successively clamped web portions, and while still at the primary station one side of each successive bag member is opened and a tag inserted between the bag layers of the doubled web. The tag members are formed from a continuous strip of tag forming material, which strip is intermittently advanced in timed relation to the web advancing, bag cutting and bag opening mechanisms, as will be more fully described hereinafter. Prior to the longitudinal doubling of the web 10a, suitable sewing machines (not shown) are employed for sewing the hems 12 at both longitudinal edges of the web, all this being substantially in accordance with the teachings of my prior Patent No. 2,313,433, already mentioned or of my Patent No. 2,667,132.

It will be noted, however, that whereas in my prior Patent No. 2,313,433 the tags or labels are inserted between two layers of a continuously moving doubled web, in accordance with the present invention the tags or labels are inserted into the sides of successive bag members which have already been cut from the web, each of which bag members is firmly clamped in stationary position, while successive tags are inserted into the successive clamped bag members at the primary station. This makes possible the accurate positioning of the tag or label with reference to the bag, which was impossible in accordance with my prior patent wherein the tag or label was inserted between the folds of a moving web. Moreover, while in accordance with my prior Patent No. 2,313,433 a special sewing machine is required to sew the tags into the closed bottom of the folded web material, the necessity for such special machine is eliminated in accordance with the present invention, and instead of such machine one of the usual sewing machines employed for sewing together the sides of the individual bag members also serves to secure the tags or labels into successive bag members. In this manner not only is a more accurate and convenient arrangement of the tags or labels within the bag insured, but an entire sewing machine is eliminated, resulting in a marked saving in the cost of the apparatus as a whole, and in addition the individual bags resulting from the use of my improved method and apparatus are more satisfactory to the industry than were the bags produced in accordance with the method and apparatus of my prior Patent No. 2,313,433.

Knife means are provided for severing the web along a line 19 at one side of the primary station 18, while temporarily clamped at said station so as to result in the formation of a series of partly completed, individual bag members 10 each of which has superposed but free or unsecured side edges 15 at the opposite sides thereof.

The tags or labels 13 are fed from a suitable roll in the form of a continuous strip 13a to the primary station 18, at which point means are provided for opening or separating the free side edges at one side of the clamped bag 5 and permitting insertion of the leading tag in the strip into the bag so that an edge of the inserted tag is disposed between the separated edges of the bag. The leading tag is then severed from its strip and the individual bag with the inserted tag is then delivered by mechanical means to 10 what may be called a secondary work station 20 having a pair of sewing machines 21 located thereon so as to secure the free side edges 15 of the bag together by the lines of stitching 16, and simultaneously secure the tag 13 in place between the side edges at one side of the bag. The lines of stitching 16 continue uninterrupted from bag to bag, so that the bags emerge in a chain fashion in readiness for delivery to the stringing machine.

Referring now to the accompanying drawings in detail, the machine in accordance with the invention comprises 20 a suitable framework 22 supporting a stationary bag supporting top plate member 23 on which the primary and secondary work stations 18, 20 are located in adjacent relationship, longitudinally of the bag being formed. The rollers 17 through which the doubled web 10c is intermittently fed to the station 18 are located at one side of the primary station 18, being mounted on a pair of shafts 24 which are simultaneously rotated by intermeshing gears 25, as is best shown in FIGURE 4. The lower of the shafts 24 carries a conventional over-running clutch 26 30 having a pinion 27 affixed thereto, the pinion, in turn, meshing with a toothed segment 28 which is pivoted at 29 to the frame 22. A link 30 extends from the segment 28 to a cam shaft 31 journaled in the frame 22 and has a yoke portion 30a which slidably straddles the camshaft as 35 shown in FIGURE 4. The yoke portion 30a carries a follower 30b which operatively engages a suitable groove (not shown) in the side of a cam 32 secured to the shaft 31. A suitable reduction gear box 33 is provided for driving the camshaft 31 as shown in FIGURE 16, the box 33 having a drive pulley 34 driven by an endless belt, or the like, from a suitable electric motor (also not shown). It will be apparent from the foregoing that when the cam shaft 31 is rotated, the rod 30 will impart an oscillatory movement to the segment 28 which, in turn, will drive the rollers 17 intermittently and unidirectionally 40 through the clutch 26 so as to feed the web 10c, step-by-step, to the primary station 18. During each step of its feeding movement, the web is advanced to the station 18 by a distance equivalent to the width of one bag to be fabricated. At the primary station 18 the web portion is temporarily gripped or clamped to the stationary top plate 23 and successive individual bag portions are cut from the main body of the web, successive tags or labels are inserted laterally between the two layers of each successive bag member, prior to stitching the sides of such bag members, and at the same time sewing the labels in place within the bags.

As shown, means are provided on the top 23 beyond the rollers 17 for severing individual bags 10 from the web 10c, these means comprising a rotary knife or cutter 35 supported by a carrier 36 which is slidable on an elongated guide 37, as shown in FIGURES 3, 5 and 6. The cutter 35 traverses the web 10c along the line 19 shown in FIGURE 2, the guide 37 being parallel to this line. The guide 37 is pivoted at one end thereof as shown at 38 to an upstanding bracket 39 on the top 23 and is adapted for raising and lowering movement relative to the top 23 by means of a link 40 which is pivoted at 41 to the other end of the guide and extends downwardly 50 therefrom, as shown. A suitable bracket 42 extends upwardly from the frame 22 and has a forked upper end portion 42a which receives the guide 37 therein, whereby to prevent lateral deflection of the guide. When the guide 37 is lowered by the link 40, the cutter 35 is brought against the top 23 to sever the web 10c along 55 70 75

the line 19 while the carrier 36 slides along the guide in the direction of the arrow 43. Suitable rollers 44 are provided on the carrier 36 to engage the underside of the guide 37 and reduce friction resulting from an upward thrust on the guide when the cutter 35 is pressed against the top 23. When the carrier 36 slides along the guide in a direction opposite to the arrow 43, the guide is raised by the link 40 as indicated by the dotted lines 37a, so that the cutter 35 is ineffective.

Means are provided for clamping the web 10c against the top 23 at the station 18 to prevent the web from shifting while the cutter 35 is in operation. These means comprise a clamping bar 45 which is pivoted at the ends thereof to connecting members 46 which, in turn, are pivoted to the end portions of the guide 37, one end of the bar 45 also being pivotally connected by a link 47 to the base portion of the bracket 39. When the guide 37 is raised, the bar 45 is raised therewith as shown at 45a, but when the guide is lowered and the cutter is in operation, the bar 45 firmly clamps the web against the top 23.

The lower end of the link 40 which raises and lowers the guide 37 is pivoted at 48 to one end of a lever 49 which is pivoted at 50 to a bracket 51 on the frame 22, as shown in FIGURE 4. The free end of the lever 49 is provided with a follower 52 engaging a groove 53 in the cam 32. The cam 32 actuates the link 30 and the lever 49 in a coordinated manner so that when the guide 37 is raised, the rollers 17 feed the web 10c past the raised cutter 35 to the primary station 18 while the carrier 36 slides on the guide from the position shown by full lines to that shown by the dotted lines 36a. When the guide is lowered, however, the feeding of the web by the rollers 17 is interrupted by the clutch 26 and the web is severed along the line 19 by the cutter travelling in the direction of the arrow 43.

Reciprocation of the carrier 36 on the guide 37 is effected by a link 54 which is pivoted at one end thereof to the carrier and, as shown in FIGURE 18, has its other end pivoted to a curved arm 55. The latter is pivoted at 56 to a bracket 57 on the frame 22 and is pivotally connected by a link 58 to a cam lever 59 which is pivotally mounted at one end thereof on a shaft 61 mounted in the frame 22 adjacent and parallel to the camshaft 31. The lever 59 carries a follower 62 which engages a groove in another cam 63 secured to the shaft 31. (See FIGURE 16.)

It will be observed from the foregoing that just before and immediately after an individual, partly completed bag member 10 has been severed from the web 10c by the cutter 35, it lies stationary on the primary station 18 in readiness for application of the tag 13 thereto. As is best shown in FIGURES 2, 3 and 20, the tags 13 are supplied in the form of a continuous strip 13a from a suitable roll 13b carried on a shaft 64 in the frame 22, the strip 13a passing over a roller 65 on a shaft 66 journalled in side members 22a of the frame. The roller 65 is preferably flanged and freely rotatable. After passing over the roller 65, the strip 13a travels toward the primary station 18 along the top 23 between a pair of spaced parallel guide rails 67 which are suitably affixed to the top 23. The strip 13a is fed intermittently to the station 18 by means hereinafter to be described, and it may be noted that the strip is provided at longitudinally spaced points thereon with markings 68 which are located at the division lines between the adjacent tags in the strip and are subject to detection by a photo-electric cell 69 which controls the intermittent feeding movement of the strip, as will be hereinafter explained. The cell 69 is mounted by means of a suitable bracket 70 on the top 23 so as to scan the tag strip 13a passing between the guide rails 67 and detect the markings 68 thereon.

With reference now to the accompanying FIGURES 3 and 8-13, means are provided for separating the free, superposed edges 15 at one side of the individual bag 10 to facilitate insertion of the tag 13 between such side

edges while the bag is at the primary station 18, these separating means comprising a pair of coacting suction heads 71, 72 which in detail are best shown in FIGURES 14 and 15. The lower suction head 71 is in the form of a chamber secured to the underside of the top 23 and provided with a plurality of apertures in register with similar bores or apertures 73 in the top 23, the chamber of the head 71 also having a nipple 74 in communication with a suction line or hose 75. When a bag 10 is resting on the stationary top plate member 23 at the primary station 18, the free side edge portion of the lower or underlying wall of the bag covers the apertures 73 so that when air is exhausted from the chamber 71 through the hose 75, the free side edge portion of the lower wall of the bag is firmly held against the top 23 by atmospheric pressure.

The upper suction head or unit 72 is in the form of an elongated member or bar having an elongated chamber 72a therein, from which air may be exhausted through the medium of a suction line or hose 76, connected to a nipple 77 at one side of the head. A plurality of suction cups 78 are mounted in a recess 79 at the underside of one end portion of the head 72 and the interior of these suction cups communicates with the chamber 72 through suitable openings 80, as will be clearly apparent.

The head or unit 72 is provided intermediate the ends thereof with an upstanding bracket 81 which is pivoted at 82 to a similar bracket 83 secured to the top 23, whereby the unit 72 is adapted for rocking movement relative to the top 23 so as to raise or lower the suction cups 78 relative to the top. It will be apparent from the foregoing that when the air in the chamber 72a is exhausted through the line 76, the free side edge portion of the upper or overlying wall of the bag 10 will adhere to the cups 78 by virtue of atmospheric pressure. Moreover, when the head 72 is rocked about the pivot 82 in the direction of the arrow 84 in FIGURE 14, that is, from its initial position shown in FIGURES 10 and 11 to the raised position shown in FIGURE 12, the free side edge portion of the upper or overlying wall of the bag will be raised and separated from the lower or underlying wall which is held relatively stationary on the top 23 by the lower suction head 71. This resultant separation of the free edge portions of the walls at one side of the bag facilitates the insertion of the leading tag in the tag strip 13a therebetween.

The suction head 72 is raised and lowered about its pivot 82 by a rod 85 which is pivoted at 86 to the free end of a reversely curved bar 87, the latter being welded or otherwise secured to the top of the head 72 and projecting longitudinally as well as laterally therefrom. The rod 85 passes downwardly through the top 23 and, as is best shown in FIGURE 17, is pivoted to a bell crank 88 which, in turn, is pivoted at 89 to a suitable bracket 90 at the underside of the top 23. The other arm of the bell crank 88 is pivotally connected to a link 91 extending to a cam lever 92 pivotally mounted on a shaft 93 which is adjacent and parallel to the shafts 31 and 61 in the frame 22. The lever 92 is equipped with a follower (not shown) engaging a suitable groove 94 in a cam 95 affixed to the camshaft 31. The shaft 93 is mounted in suitable brackets 96 on the frame 22.

A cutter blade or knife 97 is secured by suitable screws 98 to the suction head 72 for raising and lowering movement therewith, this blade being disposed transversely of the path of travel of the tag strip 13a between the guide rails 67, so as to sever the leading tag in the strip 13a after the tag has been inserted between the separated free edges at one side of the bag 10 lying on the station 18. The operation of the knife 97 will be referred to again at a later part of this specification.

Clamp means are provided for temporarily pressing successive bag members against the fixed top plate 23 at the station 18 and tensioning each successive bag member to separate the top wall thereof from the suction head 72 after insertion of the tag, as best shown in FIGURES 8

to 13. These clamp means involve the provision of a rocker arm 99 which is pivoted at 100 to the aforementioned bracket 83 and is equipped at its lower end with a clamp member 101, pivotally attached to the rocker arm at 102. The member 101 is angulated in a horizontal plane to extend laterally under the suction head 72 as shown in FIGURE 9, into an operative engagement with the upper or overlying wall of a bag on the station 18. The clamp member 101 is sustained in substantial parallel relation with the top 23 by a leaf spring 103 which engages the member 101 and is secured to the rocker arm 99 as shown in FIGURE 8.

The rocker arm 99 together with the clamp member 101 is movable between a lowered or clamping position shown in FIGURES 10 and 11, and a raised or released position shown in FIGURE 12, regardless of the raising and lowering movement of the suction head 72, so that the member 101 may clamp the bag on the station 18 even when the suction head 72 is raised, as illustrated in FIGURE 13. The rocker arm 99 is actuated by a link or rod 104 which is pivoted to a lever 105 welded or otherwise secured to the arm 99. The link 104 passes downwardly through the top 23 and is pivoted to a cam lever 106 which, in turn, is pivoted at 107 to the aforementioned bracket 51 and is equipped with a follower 108 in engagement with the periphery of the cam 32.

To prevent any lateral shifting or deflection of the suction head 72 and the associated knife 97, the suction head is biased laterally against a stop 109 on the top 23 by a tension spring 110 which extends from the pivot 86 to a suitable anchoring screw 111 on one of the guide rails 67.

The aforementioned lines or hoses 75, 76 for exhausting air from the chambers of the suction heads 71, 72 are connected to a T coupling 112 disposed at the top of a tubular housing 113 of a valve assembly 114 which is secured to the frame 22 by a suitable bracket 115. The underside of the housing 113 is provided with a nipple 116 which is in diametrical alignment with the T 112 and communicates through the medium of a suitable hose 117 with a motor-driven vacuum pump (not shown). A piston 118 is reciprocable in the housing 113 and is provided with a diametrically extending valve port or bore 119 which is registerable with the T 112 and nipple 116 when the piston is slid inwardly in the housing by an actuating rod 120, in the direction of the arrow 121 in FIGURE 23. In the inwardly slid position of the piston, the port 119 establishes communication between the vacuum pump and the suction heads 71, 72, but when the piston 118 is slid outwardly to the position shown in FIGURE 23, both the T 112 and the nipple 116 communicate with the atmosphere through the adjacent open end of the housing 113 so that the suction heads are de-energized while air from the atmosphere is drawn into the vacuum pump.

The valve actuating rod 120 is pivoted to a cam lever 122 on the aforementioned shaft 93, the lever 122 having a suitable follower (not shown) engaging a cam track or groove (also not shown) in a cam 123 on the camshaft 31, as indicated in FIGURE 16.

Feeding of the tag strip 13a to the primary station 18 is effected in an intermittent manner by means including a feed roller 124 secured to a shaft 125 journaled in the frame members 22a. The roller 124 is preferably rubber-tired for proper frictional engagement with the underside of the tag strip 13a, it being noted that for this purpose the upper portion of the roller 124 is disposed in a recess or opening 126 in the top 23, as illustrated in FIGURE 17. The roller 124 is actuated by an oscillatory crank arm 127 affixed to the shaft 125 and connected by a rod or link 128 to a cam lever 129 on the shaft 93, as shown in FIGURE 16. The lever 129 carries a suitable follower engaging a cam track in a cam 130 on the shaft 31. A freely rotatable coating roller 131 is rotatably mounted in a yoke 132 supported on a shaft 133 which is mounted above the top 23 in suitable bear-

ings 134, the shaft 133 also carrying a rocker arm or crank 135 whereby it may be partially rotated to raise and lower the yoke 132 so that the roller 131 either presses the tag strip 13a against the feed roller 124, or, in the raised position of the yoke, leaves the tag strip relatively free so that no feeding movement is imparted thereto by the feed roller. The yoke 132 is raised through the medium of the shaft 133 by a link 136 pivoted to the arm 135, the link 136, in turn, constituting or being connected to a reciprocable armature of a solenoid 137 affixed to the frame member 22a, as shown in FIGURE 24. However, the yoke 132 is biased to its lowered position wherein the roller 131 presses the tag strip against the feed roller 124, this being effected by a compression spring 138 positioned on the top 23 within an inverted cup 139 provided on an arm-like extension 140 of a collar 141 which is secured to the shaft 133, as illustrated in FIGURE 22.

It will be apparent from the foregoing that when the yoke 132 is lowered by the spring 138 and the feed roller 124 is rotated by the crank 127 in the direction of the arrow 142 in FIGURE 20, the tag strip 13a will be fed or advanced along its path between the guide rails 67 toward the primary station 18. The extent of this feeding movement is such as to advance the tag strip by a distance corresponding to the dimension of one tag 13, that is, the distance between adjacent markings 66 on the tag strip 13a. On the other hand, when the roller 124 is turned by the crank 127 in a direction opposite to the arrow 142 and the yoke 132 is raised by the solenoid 137, no feeding movement will be imparted to the tag strip.

The solenoid 137 is in circuit with a suitable source of current and remains energized until the current supply is interrupted by a switch 143 which is secured to the frame 22 and is actuated by a follower roller 143a engaging a cam track 144 on the periphery of the cam 32. Upon de-energization of the solenoid 137 by the switch 143, the spring 138 automatically lowers the yoke 132.

The intermittent feeding of the tag strip 13a is coordinated with the separation of the free edges at one side of the bag 10 on the station 18 by the suction heads 71, 72, so that when these edges are separated, the tag strip is advanced by a distance equivalent to one tag, whereby the leading tag in the strip is inserted into the bag, with an edge of the leading tag disposed between the separated bag edges. The suction head 72 is then brought down so that the knife blade 97 severs the leading tag from its strip, and the partly completed bag is now ready for further processing.

For this purpose the bag together with the inserted tag are shifted or delivered from the primary station 18 to the secondary station 20 which has the sewing machines 21 located at its opposite sides, so as to secure together the free edges at both sides of the bag by the lines of stitching 16 and simultaneously secure the tag 13 between the free edges at the side of the bag where it has been inserted.

The means for delivering the bag and the inserted tag from the station 18 to the station 20 involve the provision of an elongated guide 145 which is secured at one end thereof to a collar 146 on a stub-shaft 147 journaled in bearings 148 on the frame 22. The other end of the guide 145 has secured thereto a rigid arm 149 which, in turn, is pivoted at 150 to an actuating rod 151 passing downwardly through the top 23. The lower end of the rod 151 is pivoted to a cam lever 152 on the aforementioned shaft 61, the lever 152 having a suitable follower 153 (see FIGURE 16) engaging a cam track in a cam, namely, the cam 130, on the shaft 31. By virtue of this arrangement, the guide 145 may be raised and lowered relative to the top 23, as will be apparent. A carrier 154 is reciprocable on the guide 145 by means of an actuating rod 155 which extends between the carrier and an oscillatory crank 156 the latter being mov-

able in a horizontal plane and affixed to the upper end of a shaft 157 journalled vertically in suitable bearing means 158 provided on the frame 22. The lower end of the shaft 157 carries a crank 159 which, as shown in FIGURE 16, is connected to a cam lever 160 having a follower 161 engaging a suitable groove or track in the aforementioned cam 63.

As is best shown in FIGURES 10 and 11, the carrier 154 is provided at the underside thereof with a bearing block 162 in which is rigidly secured a cross-shaft 163 having a pair of arms 164 rigidly secured thereto, whereby the arms 164 are rigid and stationary relative to the carrier. The free ends of the arms 164 have pivotally connected thereto at 165 a pair of presser feet 166, one for each arm, and leaf springs 167 are provided on the arms to engage the presser feet and maintain the same substantially parallel with the top 23 when the guide 145 is lowered as shown in FIGURES 11 and 12. With the guide 145 lowered and the carrier 154 at the end of the guide adjacent the shaft 147, sliding of the carrier in the direction of the arrow 168 in FIGURE 11 will cause the presser feet 166 to slide the bag and the inserted tag from the primary station 18 to the secondary station 20 for operative engagement of the side edges of the bag by the sewing machines 21. Then, when the carrier 154 reaches the end of its travel at the station 20, the guide 145 is raised, thus raising the carrier and the presser feet 166 therewith and permitting return of the carrier to its initial position with the feet 166 in their raised position, in readiness for subsequent lowering and engagement with the next bag.

Apart from the presser feet 166 which deliver the bag from the primary to the secondary station, the bag is also engaged during this travel by an arcuate finger 169 which is secured at one end thereof to a shaft 170 pivotally mounted in a bearing 171 at the underside of the carrier 154. The finger 169 extends over and beyond the shaft 163 and is provided at its free end with a pivotally mounted finger piece 172 with twin prongs 172a which are adapted to engage the bag at a point overlying the tag 13 inserted therein. The finger piece 172 engages the bag while the carrier 154 is in its initial position as shown in FIGURE 11. However, when the suction head 72 is raised to separate the edges of the bag for insertion of the tag therebetween, a detent in the form of a screw 173, provided on the bar 87 engages the underside of a roller 174 mounted on a stub shaft 175 on the finger 169, whereby the finger and the associated finger piece 172 are raised out of engagement with the bag to permit insertion of the tag therein, as shown in FIGURE 12. With the lowering of the suction head 72, the finger piece 172 is again brought in contact with the bag at a point overlying the inserted bag and so remains during the travel of the carrier 154 to the secondary station 20. When the carrier 154 is in the position shown in FIGURE 10, that is, remote from the suction head 72, and the guide 145 is raised as shown, the finger 169 simply drops downwardly somewhat, to the extent permitted by engagement of the stub shaft 175 with the top edge of the adjacent of the arms 164.

Suitable guide members or rails 176, 177 are provided on the top 23 at opposite sides of the bag travelling from the primary to the secondary station, such members or rails being equipped with slotted mounting bases 178 to achieve mounting screws 179, whereby the positioning of the guides on the top 23 may be adjusted. Also, a wire spring 180 is affixed to one of the screws 179 and extends into the path of the bag travelling to the station 20 to prevent possible creasing or other displacement of the bag in that region.

The bag with the inserted tag is conveyed past the sewing machines 21 by pairs of feed rollers 181 mounted, as is best shown in FIGURE 7, on parallel shafts 182 suitably journalled in the machine and connected for simultaneous rotation by suitable gearing 183. One of the shafts 182 is driven by an endless belt or gearing (not

shown) to the source of power which drives the aforementioned pulley 34.

A gravity actuated arm 184 is pivotally mounted on the upper of the shafts 182 and carries a roller 185 which urges the bags travelling to the secondary station 20 so that they lie flat on the top 23, the roller 185 cooperating with a similar roller 186 mounted on a shaft 187 under the top 23, as shown in FIGURE 7. After passing through the rollers 185, 187 and pairs of rollers 181, the bags are delivered to the stringing machine, as indicated in FIGURE 3.

A rigid guide plate 188 is secured to the suction head 72 above the station 18 so as to guide the leading edge of the web 10a under the suction head. Similarly, a wire guide 189 is provided transversely of the guide rails 67 adjacent the roller 65 (FIGURES 3 and 20) in slightly spaced relation above the top 23, to guide the tag strip 13a between the rails 67. Moreover, the tag strip 13a is tensioned during its travel between the rails 67 toward the station 18 by means of a leaf spring 190 which, as shown in FIGURE 20, is secured to the underside of a bracket 191 which bridges the path of the tag strip between the rails 67 and is secured to the top 23. The spring 190 is normally pressed downwardly against the tag strip by a lever 192 pivoted to the bracket 191, but this lever may be released to permit upward bending of the spring and thereby facilitate feeding of the tag strip to the primary station by hand, when necessary, such as for example, when the machine is initially set in operation or after the passage of the tag strip to the primary station is for some reason interrupted. With further reference to FIGURE 16, it may be noted that suitable spacer sleeves 193 are provided on the shafts 61, 93 to separate the respective cam levers 59, 152 and 91, 120, 128 thereon, and that suitable brackets 194 are provided on the frame 22 for the camshaft 31.

Although the operation of the invention will be understood from the foregoing disclosure, it may be summarized as follows:

Operation

The web 10a unwound from the roll 10b and hemmed at its longitudinal edges as shown at 12 is doubled longitudinally upon itself as indicated at 10c and is fed by the rollers 17 intermittently to the primary station 18 while the guide 37 is raised and the knife carrier 36 travels to the position 36a shown in FIGURE 5. When feeding of the web is interrupted by the clutch 26, the guide 37 is lowered and the cutter or knife 35 severs an individual bag 10 from the web during movement of the carrier 36 in the direction of the arrow 43.

The severed bag remains temporarily stationary on the primary station 18 and, with the guide 145 and carrier 154 in the position shown in FIGURE 11, the suction heads 71, 72 are energized by the valve 114 and as the upper suction head 72 is raised to separate the edges of the bag for insertion of the tag, the finger piece 172a is raised simultaneously by engagement of the roller 174 with the screw 173 to facilitate such an insertion, as illustrated in FIGURE 12. In this regard it may be noted that although the head 72 is raised, the guide 145 remains lowered and the presser feet 166 remain in engagement with the bag, thus clamping the bag against the top 23.

The tag strip 13a is then advanced toward the station 18 by the feed roller 124 so that the leading tag in the strip is inserted in the bag with an edge thereof disposed between the separated edges of the bag. When the leading tag is inserted to the appropriate extent, the photo-electric cell 69, responding to the markings 66 on the tag strip, energizes the solenoid 137 so as to raise the roller 131 and interrupt the feeding movement of the tag strip. The tag strip then remains stationary until the roller 131 is again lowered by interruption of flow of current to the solenoid through the switch 143 for the subsequent cycle of operation. After insertion of

the tag into the tag, the rocker arm 99 is moved by the rod or link 104 so that the clamp member 101 moves downwardly and away from the top or mouth of the bag, the latter being held clamped against the top 23 by the presser feet 166. When the member 101 comes in contact with the bag lying on the top 23, downward movement of the member 101 is arrested and continued actuation of the rocker arm 99 causes the spring 103 to apply pressure on the clamp member 101 so that it moves away from the top or mouth of the bag and pulls the upper wall of the bag away from the suction head 72 so that it lies tightly upon the bottom wall of the bag and the edge portion of the tag inserted between the bag walls. By having the bag stretched tightly between the presser feet 166 and the clamp member 101, the two leading corners of the tag do not catch or hang on the bag walls while the tag slides to the limit of its insertion into the bag.

The lowering of the suction head 72 causes the knife 97 to sever the leading tag from the tag strip 13a and after this severing operation is completed, the head 72 returns to its initial, raised position. By that time, the presser feet 166 which are already in engagement with the bag and the finger piece 172 which has been brought into contact with the bag by the lowering of the head 72, coact with the sliding movement of the carrier 154 on the guide 145 in the direction of the arrow 168 and thereby deliver the bag and the inserted tag to the secondary station 20, where the sewing machines 21 stitch the side edges of the bag and the tag therebetween.

Upon delivery of the bag to the secondary station, the guide 145 with the carrier 154 is raised, thus disengaging the feet 166 as well as the finger piece 172 from the bag and facilitating return of the carrier to its initial position for the next cycle of operation. In the meantime, the rollers 181 cause the bag to travel past the sewing machines 21 for delivery to the stringing machine.

It may be noted that the screw 173 is adjustable as to height in the bar 87 with respect to proper setting for engagement with the roller 174 and may be locked in a pre-adjusted position by a set screw 195.

Although the machine is primarily intended for the manufacture of bags of cotton or like fabric material, having stitched hems 12 and lines of stitching 16 at the sides thereof, it may be also used for production of bags of plastic, or the like, wherein heat sealing is substituted for the stitching operations.

Thus, while in the foregoing there has been described and shown the preferred embodiment of the invention, various modifications may become apparent to those skilled in the art to which the invention relates. Accordingly, it is not desired to limit the invention to this disclosure and various modifications may be resorted to, such as may lie within the spirit and scope of the appended claims.

What is claimed as new is:

1. In a bag making and tagging machine, the combination of a primary station adapted to receive a partly completed individual bag having superposed, but free edges at least at one side thereof, means at said primary station for separating and closing the superposed free edges of the bag, means for inserting a tag between the separated edges, a secondary station, means for delivering a bag with its inserted tag from the primary to the secondary station, and bag edge sewing means provided at said secondary station for securing the free edges of the bag together with the tag secured therebetween by said sewing means.

2. In a bag making and tagging machine, the combination of a primary station adapted to receive a partly completed individual bag having superposed but free edges at least at one side thereof, means at said primary station for alternately separating and closing the superposed free edges of the bag, means for intermittently feeding a continuous strip of tags to said primary sta-

tion and inserting an edge of the leading tag in said strip between the free edges of the bag when the same are separated, means for severing the leading tag from its strip, a secondary station, means for delivering a bag with its inserted tag from the primary to the secondary station, and bag edge sewing means provided at said secondary station for securing the free edges of the bag together with the tag secured therebetween by said sewing means.

3. In a bag making and tagging machine, the combination of a primary station, means for feeding partly completed bags in continuous web form to said primary station, means for severing individual bags from the web at the primary station whereby the individual bag

15 has superposed but free edges at least at one side thereof, means at the primary station for alternately separating and closing the superposed free edges of the bag, means for inserting a tag between the free edges when the same are separated, a secondary station, means for delivering a bag with its inserted tag from the primary to the secondary station, and bag edge sewing means provided at said secondary station for securing the free edges of the bag together with the tag secured therebetween by said sewing means.

4. In a bag making and tagging machine, the combination of a primary station, means for feeding partly completed bags in continuous web form to said primary station, means for severing individual bags from the web at the primary station whereby the individual bag has super-

posed but free edges at least at one side thereof, means at the primary station for alternately separating and closing the superposed free edges of the bag, means for intermittently feeding a continuous strip of tags to the primary station and inserting an edge of the leading tag in said strip between the free edges of the bag when the same are separated, means for severing the leading tag from its strip, a secondary station, means for delivering a bag with its inserted tag from the primary to the secondary station, and bag edge sewing means provided at said secondary station for securing the free edges of the bag together with the tag secured therebetween by said sewing means.

5. In a bag making and tagging machine wherein a continuous web of material is doubled longitudinally upon itself to form the side walls and closed bottom of bags 45 with an open mouth and is fed intermittently to a primary station, knife means provided at one side of said primary station for severing individual bags from the web whereby the individual bag has superposed but free edges at the opposite sides thereof, means provided at the other side of said primary station for alternately separating and closing the superposed free edges of the bag at that side, means for inserting a tag within the bag so that an edge of the tag is disposed between the separated free side edges of the bag, bag edge sewing means provided adjacent said primary station, and means for delivering a bag with its inserted tag from the primary station to said sewing means for securing together the free edges at both sides of the bag and the inserted tag.

6. In a bag making and tagging machine wherein a continuous web of material is doubled longitudinally upon itself to form the side walls and closed bottom of bags with an open mouth and is fed intermittently to a primary station, knife means provided at one side of said primary station for severing individual bags from the web whereby the individual bag has superposed but free edges at the opposite sides thereof, means provided at the other side of said primary station for alternately separating and closing the superposed free edges of the bag at that side, means for intermittently feeding a continuous strip of tags to the primary station and inserting the leading tag in said strip within the bag so that an edge of the leading tag is disposed between the separated free side edges of the bag, means for severing the leading tag from its strip, bag edge sewing means provided adjacent said primary station, and means for delivering a bag with its inserted

70 tag from the primary station to said sewing means for securing together the free edges at both sides of the bag and the inserted tag.

tag from the primary station to said sewing means for securing together the free edges at both sides of the bag and the inserted tag.

7. In a bag making and tagging machine, the combination of a primary station, means for feeding partly completed bags in continuous web form to said primary station, knife means provided at one side of the primary station for severing individual bags from the web whereby the individual bag has superposed but free edges at least at one side thereof, superposed suction units provided at the primary station in respectively underlying and overlying relation to the primary station and to the superposed free edge portions of the bag supported thereon whereby said edge portions may adhere thereto when the suction units are energized, means for moving one of said suction units alternately away from and toward the other whereby the free edges of the bag may be alternately separated and closed, means for inserting a tag between the edges of the bag when separated, bag edge sewing means provided adjacent the primary station, and means for delivering a bag with its inserted tag from the primary station to said sewing means for securing the free edges of the bag together and the tag therebetween.

8. In a bag making and tagging machine, the combination of a primary station, means for feeding partly completed bags in continuous web form to said primary station, knife means provided at one side of the primary station for severing individual bags from the web whereby the individual bag has superposed but free edges at least at one side thereof, superposed suction units provided at the primary station in respectively underlying and overlying relation to the primary station and to the superposed free edge portions of the bag supported thereon whereby said edge portions may adhere thereto when the suction units are energized, means for moving one of the suction units alternately away from and toward the other whereby the free edges of the bag may be alternately separated and closed, means for intermittently feeding a continuous strip of tags to the primary station and inserting an edge of the leading tag in said strip between the edges of the bag when separated, knife means carried by the movable suction unit for severing the leading tag from its strip, bag edge sewing means provided adjacent said primary station, and means for delivering a bag with its inserted tag from the primary station to said severing means for securing the free edges of the bag together and the tag therebetween.

9. In a bag making and tagging machine wherein a continuous web of material is doubled longitudinally upon itself to form the side walls and closed bottom of bags with an open mouth and is fed intermittently to a primary station, knife means provided at one side of said primary station for severing individual bags from the web whereby the individual bag has superposed but free edges at the opposite sides thereof, superposed suction units provided at the other side of said primary station in respectively underlying and overlying relation to the primary station and to the superposed free edge portions of the bag supported thereon at that side whereby said edge portions may adhere thereto when the suction units are energized, means for moving one of the suction units alternately away from and toward the other whereby the adjacent free edges of the bag may be alternately separated and closed, means for intermittently feeding a continuous strip of tags to the primary station and inserting the leading tag in said strip within the bag so that an edge of the leading tag is disposed between the separated free side edges of the bag, knife means carried by the movable suction unit for severing the leading tag from its strip, a secondary station, bag edge sewing means provided at both sides of said secondary station, and means for delivering a bag with its inserted tag from the primary to the secondary station for securing together the free edges at both sides of the bag and the inserted tag by said sewing means.

10. The device as defined in claim 9 wherein said first mentioned knife means including a carrier reciprocable along one side of said primary station, means for reciprocating the same, and a rotary cutter mounted on said carrier.

11. The device as defined in claim 9 wherein said first mentioned knife means include an elongated guide extending along one side of said primary station and movable toward and away from the same, a carrier reciprocable on said guide, means for reciprocating said carrier, a rotary cutter mounted on the carrier for cooperation with the primary station when the guide is moved toward the latter, and means for moving said guide.

12. The device as defined in claim 9 wherein said means for delivering a bag from the primary to the secondary station include an elongated guide extending from one station to the other and movable toward and away from the same, a carrier reciprocable on said guide, means for reciprocating said carrier, a presser foot supported by the carrier and adapted to engage a bag on the primary station when the guide is moved toward the latter, and means for moving said guide.

13. The device as defined in claim 9 wherein said means for delivering a bag with its inserted tag from the primary to the secondary station include an elongated guide extending from one station to the other and movable toward and away from the same, a carrier reciprocable on said guide, means for reciprocating said carrier, a presser foot supported by the carrier and adapted to engage a bag on the primary station when the guide is moved toward the latter, means for moving said guide, a finger pivoted to said carrier for movement toward and away from the primary station and adapted to engage a bag at a point overlying its inserted tag, and means for moving said finger independently of the movement of said guide.

14. The device as defined in claim 9 together with means for clamping a bag against said primary station after separation of the superposed edges thereof by said suction units.

15. The device as defined in claim 9 together with means for clamping a bag against said primary station after separation of the superposed edges thereof by said suction units, said last mentioned means comprising a pivotally mounted clamp member disposed at one side of the primary station and movable toward and away from the same, and means for moving said clamp member.

16. The device as defined in claim 9 wherein each tag in the strip is provided with a mark, together with means including a photoelectric cell adapted to scan the strip of tags and detect the marks thereon for controlling the intermittent feeding of the strip to said primary station.

17. In a bag making and tagging machine, a primary station including a fixed bag supporting top plate portion adapted to support successive partly completed bag members each provided with a pair of superposed but free edges, means for holding one free edge portion of a bag member stationary on said fixed top plate member, means comprising a relatively movable suction unit engageable with the other free edge portion of the bag member for moving the same away from the stationary edge portion, whereby to facilitate insertion of a tag therebetween, means for inserting a tag between said separated edges, means for releasing the edge portion which has been moved away from the other edge portion, and means for uniting the free edge portions and simultaneously securing the tag between them.

18. In a bag making and tagging machine, a primary station including a fixed bag supporting top plate member adapted to support thereon successive partly completed bag members each provided with a pair of superposed but free edges, means for temporarily clamping successive bag members to said top plate, a pair of suction units engageable with the respective free edge portions

of a bag member clamped upon said plate, means for moving one suction unit away from the other, whereby to separate the free edges of the bag member and facilitate insertion of a tag therebetween, means for inserting a tag between the separated edge portions of the clamped bag member, means for cutting off suction from said suction units after insertion of the tag, and means for uniting the said free edges of the bag member with the tag secured between them.

19. The device as defined in claim 18 wherein at least one of said suction units includes a plurality of suction cups, and means for exhausting air from said cups.

20. A bag making and tagging machine as set forth in claim 18, wherein the top plate member is perforated and one of the suction units is located below and the other above the perforated top plate member.

21. In a bag making and tagging machine, the combination of a primary station adapted to receive a partly completed individual bag having superposed but free edges at least at one side thereof, means at said primary station for separating and closing the superposed free edges of the bag, means for inserting a tag between the separated edges, a secondary station, means for delivering a bag with its inserted tag from the primary to the secondary station, and bag edge sewing means provided at said secondary station for securing the free edges of the bag together with the tag secured therebetween by said sewing means, the primary station including supporting means for the free edge portions of the bag and the edge separating and closing means comprising superposed suction units in respectively underlying and overlying relation with the means supporting the superposed free edge portions of the bag whereby the same may adhere when the suction units are energized, and means for moving one of the suction units alternately away from and toward the other.

22. In a bag making and tagging machine, the combination of a primary station including a fixed bag supporting top plate adapted to receive successive partly completed separate bag members each having superposed but free edges at least at one side thereof, means for temporarily clamping a portion of each successive bag member to said top plate at said primary station, means for separating and closing the superposed free edges of the clamped bag member, means for inserting a tag between the separated edges of the clamped bag member, a secondary station, means for delivering bag members with their inserted tag from the primary to the secondary station, and bag edge sewing means provided at said secondary station for securing the free edges of successive bag members together with the tags secured therebetween by said sewing means.

23. In a bag making and tagging machine, the combination of a primary station adapted to receive successive partly completed separate bag members each having superposed but free edges at least at one side thereof, means for clamping successive bag members in fixed position at said primary station, means for alternately separating and closing the superposed free edges of successive clamped bag members, means for intermittently feeding a continuous strip of tags to said primary station and inserting an edge of the leading tag in said strip between the free edges of the bag when the same are separated, means for severing the leading tag from its strip, a secondary station, means for delivering a bag with its inserted tag from the primary to the secondary station, and bag edge sewing means provided at said secondary station for securing the free edges of the bag together with the tag secured therebetween by said sewing means.

24. In a bag making and tagging machine, the combination of a primary station, means for intermittently feeding partly completed bags in continuous web form to said primary station, means for severing successive individual bag members from the web at the primary station whereby the individual bag has superposed but free

edges at least at one side thereof, means for clamping successive bag members at said station, means at the primary station for alternately separating and closing the superposed free edges of successive bag members, means for inserting a tag between the free edges of successive clamped bag members when the same are separated, a secondary station, means for delivering a bag member with its inserted tag from the primary to the secondary station, and bag edge sewing means provided at said secondary station for securing the free edges of the bag together with the tag secured therebetween by said sewing means.

25. In a bag making and tagging machine, the combination of a primary station, means for intermittently feeding partly completed bags in continuous web form to said primary station, means for severing successive individual bag members from the web at the primary station whereby each individual bag member has superposed but free edges at least at one side thereof, means for successively clamping separate bag members at the primary station, means for alternately separating and closing the superposed free edges of the clamped bag members, means for intermittently feeding a continuous strip of tags to the primary station and inserting an edge of the leading tag in said strip between the free edges of successive clamped bag members, when the edges are separated, means for severing the leading tag from its strip, a secondary station, means for delivering successive bag members with their inserted tags from the primary to the secondary station, and bag edge sewing means provided at said secondary station for securing the free edges of the bag together with the tag secured therebetween by said sewing means.

26. In a bag making and tagging machine wherein a continuous web of material is doubled longitudinally upon itself to form the side walls and closed bottom of bags with an open mouth and is fed intermittently to a primary station, means for clamping successive portions of the web at said station, knife means provided at one side of said primary station for severing successive individual bags from the clamped web portion whereby each individual bag has superposed but free edges at the opposite sides thereof, means provided at the other side of said primary station for alternately separating and closing the superposed free edges of the clamped bag at that side, means for successively inserting tags within successive clamped bags so that an edge of each tag is disposed between the separated free side edges of its respective bag, bag edge sewing means provided adjacent said primary station, and means for delivering successive bags with their inserted tags from the primary station to said sewing means for securing together the free edges at both sides of the bag and the inserted tag.

27. In a bag making and tagging machine wherein a continuous web of material is doubled longitudinally upon itself to form the side walls and closed bottom of bags with an open mouth and is fed intermittently to a primary station, web clamping means at said station, knife means provided at one side of said primary station for severing successive individual bags from the clamped web whereby each individual bag has superposed but free edges at the opposite sides thereof, means provided at the other side of said primary station for alternately separating and closing the superposed free edges of the clamped bag at that side, means for intermittently feeding a continuous strip of tags to the primary station and inserting the leading tag in said strip within the clamped bag so that an edge of the leading tag is disposed between the separated free side edges of the bag, means for severing the leading tag from its strip, bag edge sewing means provided adjacent said primary station, and means for delivering successive individual bags each with its inserted tag from the primary station to said sewing means for securing together the free edges at both sides of the bag and the inserted tag.

28. A method of forming tagged bags, comprising the steps of severing an individual bag from a continuous web of material which is doubled longitudinally upon itself to form the side walls and closed bottom of the bag with an open mouth whereby the individual bag has superposed free edges at the opposite sides thereof, holding one free side edge portion of the bag stationary, moving the superposed side edge portion away from the stationary edge portion whereby to separate the same, inserting a tag within the bag so that an edge of the tag is disposed between the separated edges of the bag, moving the separated edge portion of the bag toward the tag and the stationary edge portion, and securing together the free edges at both sides of the bag with the tag inserted therebetween and secured between the edge portions of one side of the bag.

29. A method as defined in claim 28 wherein the edges are secured by stitching.

30. A method of forming a tagged bag which comprises severing an individual bag from a continuous web of material which is doubled longitudinally upon itself to form the side walls and closed bottom of the bag with an open mouth whereby the individual bag has superposed free edges at the opposite sides thereof, holding one free side edge portion of the bag relatively stationary, moving the superposed side edge portion away from the relatively stationary edge portion whereby to separate the same, inserting a tag within the bag so that an edge of the tag is disposed between the separated edges of the bag, moving the separated edge portion of the bag toward the tag and the relatively stationary edge portion, and securing together the free edges at both sides of the bag with the tag inserted therebetween and secured between the free edges at both sides of the bag with the tag inserted therebetween and secured between the edge portions of one side of the bag.

31. A method of forming a tagged bag which comprises severing an individual bag from a continuous web of material which is doubled longitudinally upon itself to form the side walls and closed bottom of the bag with an open mouth whereby the individual bag has superposed free edges at the opposite sides thereof, holding one free side edge portion of the bag relatively stationary, moving the superposed side edge portion away from the relatively stationary edge portion whereby to separate the same, inserting a tag within the bag so that an edge of the tag is disposed between the separated edges of the bag, moving the separated edge portion of the bag toward the tag and the relatively stationary edge portion, securing together the free edges at both sides of the bag with the tag inserted therebetween and secured between the edge portions of one side of the bag, and

then reversing the finished bag whereby the tag extends laterally from one side of the bag.

32. A method as defined in claim 30, wherein the free edges are secured by stitching.

33. A method as defined in claim 31, wherein the free edges are secured by stitching.

34. In a method of forming a tagged bag, wherein a continuous web of bag making material is doubled longitudinally upon itself whereby to form side walls, a closed bottom portion and a mouth portion opposite the bottom portion for each of successive bag members to be cut from the doubled web; the improvement which comprises intermittently clamping successive end portions of the doubled web at a primary station, intermittently severing successive individual bag members from the clamped web portions at said station whereby each successive bag member has superposed free edges at opposite sides thereof, holding one free edge portion of the bag stationary, moving the superposed edge portion away from the stationary edge portion, whereby to separate the same, inserting a tag within the bag member so that an edge of the bag member is disposed between the separated edges of the bag member, then moving the separated edge portion of the bag member toward the tag and the stationary edge portion, inserting a tag within the bag so that an edge of the tag is disposed between the separated edges of the bag member, then moving each bag member and with the tag member between the free edges at one side to a second station, and securing together the free edges of the bag with the tag secured therebetween.

35. A method as set forth in claim 34 wherein the superposed free edge is moved away from the stationary free edge by the action of suction.

36. A method as set forth in claim 34 wherein the tags of successive bags are successively inserted and cut from the free end of a continuous strip supplied from a roll, and the inserting and cutting operations are performed in timed relation to the movement of the superposed free edge portion toward and away from the stationary edge portion.
